WALTER T. DAVIS, OF WHEELING, WEST VIRGINIA. ASSIGNOR TO WHEELING STAMPING COMPANY, OF WHEELING, WEST VIRGINIA, A CORPORATION OF WEST VIRGINIA.

COLLAPSIBLE TUBE

Application filed June 25, 1927. Serial No. 201,328.

This invention relates to collapsible tubes and is particularly applicable to collapsible tubes used as containers for glue or other adhesive materials.

In collapsible tubes as now provided, the glue or other adhesive material within the tube is liable to set around the threads at the top of the sealing plug and make the removal of the plug difficult. According to the present invention there is provided an arrangement whereby the mass of glue or other adhesive material in the discharge passage of the tube may be kept moist so as to prevent the plug from becoming stuck, and to make its removal more easy.

The invention may be readily understood by reference to the accompanying drawings, in which—

Figure 1 is an elevation of a collapsible tube showing the sealing plug removed, the upper portion of the tube being shown in section;

Figure 2 is a similar view showing the sealing plug in place in the tube; and

Figure 3 is a detail view of the sealing plug.

In the drawings, 2 designates a collapsible tube of any preferred construction having a shoulder portion 3 and a neck 4. In the neck 4 is a discharge passage 5. The lower inner portion of the passage 5 is restricted, and is threaded as indicated at 6, while the outer portion of the passage is of considerably increased diameter, as indicated at 7.

The tube is sealed by means of a plug 8 having a button 9 at the top thereof and having a threaded portion 10 for cooperation with the threads in the restricted portion 6 of the tube.

When the tube is used, the adhesive material, such as glue or other material packed in the tube, is forced out of the tube through the passage 5 and the enlarged portion 7 thereof. When the plug is replaced, some of the glue will collect in the enlarged portion 7, this portion in effect constituting a reservoir for retaining a small quantity of the adhesive liquid. The button 9 will seat against the top of the tube and retain this liquid in place. By reason of the fact that

there is a small quantity of liquid trapped in the top of the tube in this fashion, the glue in the threads is prevented from hardening. Consequently, the plug may be easily removed at any time.

While I have described one specific illustration of my invention, it will be understood that various changes and modifications may be made therein within the contemplation of my invention and under the scope of the following claims.

I claim:

1. A collapsible tube having a neck portion with a discharge passage therethrough, the outer end of the discharge passage being of greater diameter than the inner portion, and a sealing plug inserted in the discharge passage, the upper portion of the sealing plug being of less diameter than the diameter of the upper portion of the discharge passage, the plug projecting beyond the end of the neck of the tube.

2. A collapsible tube having a neck portion with a discharge passage therethrough, the outer end of the discharge passage being of greater diameter than the inner portion, and a sealing plug inserted in the discharge passage, the upper portion of the sealing plug being of less diameter than the diameter of the upper portion of the discharge passage, said plug having a top thereon adapted to seat against the end of the neck of the tube, thereby forming a closed liquid retaining reservoir in the outer portion of the neck.

3. A collapsible tube having a neck portion with a discharge passage therethrough, the inner end of the discharge passage being threaded and the outer end of the discharge passage being of increased diameter, a plug removably inserted in the discharge passage having a threaded portion for engagement with the threads in the inner portion of the discharge passage, a space being provided in the outer portion of the discharge passage around the plug, said plug having a button thereon adapted to seat against the end of the neck.

4. A collapsible tube having a neck portion with a discharge passage therein, a plug retaining means in the inner portion

of the passage, the outer portion of the passage being of greater diameter than the inner portion, and a plug removably inserted in the passage, a space being provided around the plug in the outer portion of the discharge passage, the plug projecting beyond the end of the neck of the tube.

5. A collapsible tube having a body portion and a neck portion, said neck portion 10 having a discharge passage therethrough which is enlarged at its outer end to provide a reservoir for material expelled from the body of the tube, and a removable plug having an outer portion which closes the reservoir and an inner portion extending into 15 and closing the passage between the reservoir and the body.

In testimony whereof I have hereunto set my hand.

WALTER T. DAVIS.
